UNITED STATES PATENT OFFICE.

CHARLES G. KEENAN, OF OJAI, CALIFORNIA.

DESIGN FOR A TAIL LIGHT.

Application filed June 21, 1923. Serial No. 6,543. Term of patent 14 years.

To all whom it may concern:

Be it known that I, CHARLES G. KEENAN, a citizen of the United States, residing at Ojai, in the county of Ventura and State of California, have invented a new, original, and ornamental Design for Tail Lights, of which the following is a specification, reference being had to the accompanying drawing, forming part thereof.

Fig. 1 is a front elevation of a tail light, showing my new design, and

Fig. 2 is a side elevation of the same.

I claim:

The ornamental design for a tail light, as shown.

CHARLES G. KEENAN.
